United States Patent Office.

WILLIAM T. COLE, OF NEW YORK, N. Y., ASSIGNOR TO HIMSELF, JACOB F. HUNTER, AND PETER P. KELLER, OF THE SAME PLACE.

Letters Patent No. 69,184, dated September 24, 1867.

IMPROVEMENT IN CHUCKS.

The Schedule referred to in these Letters Patent and making part of the same,

TO ALL WHOM IT MAY CONCERN:

Be it known that I, WILLIAM T. COLE, of the city, county, and State of New York, have invented a new and useful Improvement in Chucks; and I do hereby declare that the following is a full, clear, and exact description thereof, which will enable others skilled in the art to make and use the same, reference being had to the accompanying drawings, forming part of this specification, in which—

Figure 1 represents a face view of my improved chuck.

Figure 2 is a similar view, the oscillating face-plate being removed.

Figure 3 is a view similar to fig. 1, showing a modification in the construction of the pawls.

Figure 4 is a central section through my improved chuck, the plane of section being indicated by the line $z z$; fig. 2.

Similar letters of reference indicate corresponding parts.

This invention consists in fitting upon the face of a revolving disk or box two or more pawls, which are pivoted to the face of the disk, and extend towards the centre of the disk to a central aperture thereon, through which aperture the tubes or rods, or other articles to be held, are passed. The ends of the pawls are so arranged that they can be turned away from the aforesaid central aperture, and that, when thrown upon the shaft, they will, when pressure is applied to the shaft or pipe by a tool or otherwise, be carried by the shaft towards the radial line of the shaft and disk, and will thus be made to clamp the shaft or pipe the tighter, the more pressure is applied to the same. For this purpose the pawls are made a little longer than the distance from their pivots to the periphery of the shaft.

A represents a cylindrical box, open at one end, and secured to the hollow spindle of a suitable lathe, so as to revolve with the same. The back of the box A has a central aperture, the diameter of the hole being a little larger than that of the pipe or shaft to be held. B B is a series of pawls, their number being regulated by the size of the machinery, and by the amount of strain to be brought against them. Each of these pawls has a knuckle, a , at its outer end, which fits into a corresponding recess in the back of the box A, as shown in fig. 2. Projecting from the side of each pawl is a pin, b , which passes through a hole in an oscillating plate, C, which is fitted within the front edges of the box A. The plate C is provided with a handle, c , by which it is moved or oscillated. The plate C is also provided with curved slats d , which pass through the pins or screws e , which are attached to the back of the box A. These screws serve to govern the oscillation of plate C, and also to attach it to the box. By means of the handle c the plate C is turned, and with it the pawls B are moved to or from the central aperture of the box A, the movement of the pawls being occasioned by the pins b , which work in holes in the plate C, as before described. The inner ends of the pawls may be formed with single points, as in fig. 3, or, as in fig. 2, with double points. When formed with double points the pawls will be adapted to hold the shaft when the same is turned in either direction, as is clearly indicated by red and black lines in fig. 2. As the pawls are longer than the distance between the centres on which they turn, and the periphery of the shaft, they will, when power is applied to the shaft, tube, or rod, by a tool or otherwise, be carried nearer to the radial line in the same ratio as the force acting against the shaft, tube, or rod is increased, and consequently they will bite the tighter upon the shaft the heavier the strain of the tool. When two points are on the pawls, as in fig. 2, they will hold, when the shaft is turned in either direction, while with one point they will only hold the shaft when it turns in the direction of the arrow in fig. 3.

The manner herein described of securing or hinging the pawls can be varied. For making the apparatus adjustable to different-sized shafts, the back of the box may be slotted, and hold the pivots of the pawls in these slots. In this case bushings would have to be provided for the hole in the centre of the disk A.

The invention is particularly applicable for holding pipes on the end of which a screw-thread is to be cut. In such a case the pipe is inserted through the central aperture of the box A, the pawls are applied, and the pipe will be carried around by the lathe; the thread is then cut, and when cut the pipe can be disengaged from the lathe by a slight move of the handle, and without stopping the machine. The pipe, when readjusted, can be again clamped by another short move of the handle. By reversing the machine the pipe is also released. Of all the chucks now in use none are fitted to allow the disengaging of the pipe or shaft while in motion.

I claim as new, and desire to secure by Letters Patent—

The combination of the pawls B, oscillating plate C, and revolving box A, all constructed and operating substantially as herein shown and described.

WILLIAM T. COLE.
